UNITED STATES PATENT OFFICE

131,177

DESIGN FOR A KEY CASE

Warner R. Buxton, Longmeadow, Mass., assignor
to Buxton, Incorporated, Springfield, Mass., a
corporation of Massachusetts

Application December 7, 1940, Serial No. 97,154

Term of patent 14 years

To all whom it may concern:

Be it known that I, Warner R. Buxton, a citizen of the United States, residing at Longmeadow, in the county of Hampden, and State of Massachusetts, have invented a new, original, and ornamental Design for a Key Case, of which the following is a specification, reference being had to the accompanying drawing, forming part thereof.

Fig. 1 is a top plan view of a key case showing my new design; and

Fig. 2 is a front elevational view thereof.

The design is confined to the front of the key case, the back being substantially plain.

The characteristic feature of the design resides in the key case disclosed, having a closure flap thereon of the specific configuration shown.

I claim:

The ornamental design for a key case, substantially as shown and described.

WARNER R. BUXTON.
